UNITED STATES PATENT OFFICE.

JOHN F. KYTLICA, OF CHICAGO, ILLINOIS.

PACKING-RING.

1,106,462.

Specification of Letters Patent. Patented Aug. 11, 1914.

Application filed April 9, 1914. Serial No. 830,597.

To all whom it may concern:

Be it known that I, JOHN F. KYTLICA, a citizen of the United States, and a resident of the city of Chicago, county of Cook, and 5 State of Illinois, have invented certain new and useful Improvements in Packing-Rings, of which the following is a specification.

My invention relates to packing rings such as are used upon piston heads and the 10 like and has for its object the production of a packing ring which, when in use, will be adapted to establish a tight connection between the piston head and the cylinder in which the same is operated by effectually 15 preventing leakage through the joints at the ends of the sections of which the ring is composed.

A further object is the production of a 20 packing ring as mentioned which will be of simple and economical construction and efficient in use.

Other objects will appear hereinafter.

With these objects in view my invention 25 consists in the combinations and arrangements of parts hereinafter described and claimed.

The invention will be best understood by reference to the accompanying drawing forming a part of this specification, and in 30 which—

Figure 1 is a front elevation of a packing ring embodying my invention, Fig. 2 is a 35 section taken on line $x-x$ of Fig. 1, Fig. 3 is a bottom plan view of Fig. 2, Fig. 4 is a plan view of one of the sections of the packing ring, and Fig. 5 is a fragmentary perspective of the section shown in Fig. 4.

The preferred form of construction as 40 illustrated in the drawing comprises a packing ring consisting of inner and outer annular split sections 1 and 2 respectively, said sections being formed of spring metal so as to permit of the same being expanded in order to slide the same over the piston head 45 into engagement with the annular grooves usually provided in the piston head for the reception of the packing rings. After being arranged in position in the grooves in the piston head the resiliency of said sections 1 and 2 serves to press the latter outwardly into engagement with the walls of the cylinder in order to establish a tight connection as is readily understood by those skilled in the art. Said sections fit one with- 55 in the other as shown, the section 1 being

provided at one edge with an outwardly turned annular radial flange 3 and said section 2 being provided at one edge with an inwardly annular radial flange 4. The flange 3 registers as shown with the unflanged edge of section 2. Provided at the opposite edge of section 1 is a longitudinally extending annular flange 5 which registers with the inner edge of the flange 4, the outer edge of flange 5 being flush with the corresponding edge of the section 2, as clearly shown in Fig. 2 of the drawing. By providing the longitudinal flange 5 upon section 1 the gap which is formed between the adjoining ends of flange at the ends 6 and 6' 60 of the section 2 is closed, as clearly shown in Fig. 3, thereby eliminating the formation of a transversely extending passage at this point which, when the ring is in use, results in leakage therethrough. 70

The respective ends 7 and 7' of the section 1 are overlapped as clearly shown in Figs. 1, 4 and 5 so as to prevent the formation of a transversely extending opening through the ring at the adjoining ends of the flange 3 of 80 said section, it being clear that without this overlapping construction a transversely extending opening in the ring would be formed between the ends of said flange which when the ring is in use, would result in leakage. 85 Thus it will be seen that with the construction set forth the joints at the respective ends of the sections or component parts of the ring will be tightly closed, precluding the possibility of leakage through the ring when 90 in use.

Provided in the section 1 midway the ends thereof is an outwardly projecting pin 8 which is positioned between the ends of section 2 so as to prevent relative rotary movement of said sections, holding the joints in said sections at diametrically opposite sides of the ring. The end 6' of the section 2 is notched or cut away at 9 in order to accommodate the pin 8 and so as to permit of the 100 ends 6 and 6' closely adjoining each other when the ring is in use.

While I have illustrated and described the preferred form of construction for carrying my invention into effect, this is capable of 105 variation and modification without departing from the spirit of the invention. I therefore, do not wish to be limited to the precise details of construction set forth, but desire to avail myself of such variations and modifica- 110

tions as come within the scope of the appended claims.

Having described my invention what I claim as new and desire to secure by Letters

5 Patent is:

1. A packing ring comprising two annular split sections fitting one within the other; an annular inwardly turned radial flange at one edge of said outer section; an annular 10 outwardly turned radial flange at one edge of said inner section, said outwardly turned flange registering with the unflanged edge of said outer section; and a longitudinally extending flange at the other edge of said 15 inner section registering with the inner edge of said inwardly turned flange, the respective ends of said inner section being slidably overlapped, substantially as described.

2. A packing ring comprising two annular 20 split sections fitting one within the other; an annular inwardly turned radial flange at one edge of said outer section; an annular outwardly turned radial flange at one edge of said inner section, said outwardly turned flange 25 registering with the unflanged edge of said outer section; and a longitudinally extending flange at the other edge of said inner section registering with the inner edge of said inwardly turned flange, the respective ends of said inner section being slidably overlapped, substantially as described.

3. A packing ring comprising two annular split sections fitting one within the other; 30 an annular inwardly turned radial flange at one edge of said outer section; an annular outwardly turned radial flange at one edge of said inner section, said outwardly turned flange registering with the unflanged edge 35 of said outer section; and a longitudinally extending flange at the other edge of said inner section registering with the inner edge of said inwardly turned flange, the respective ends of said inner section being slidably overlapped, substantially as described.

40

of said inwardly turned flange, the respective ends of said inner section being slidably overlapped, substantially as described.

45

4. A packing ring comprising two annular split sections fitting one within the other; an annular inwardly turned radial flange at one edge of said outer section; an annular outwardly turned radial flange at one edge 50 of said inner section, said outwardly turned flange registering with the unflanged edge of said outer section; a longitudinally extending flange at the outer edge of said inner section registering with the inner edge of said inwardly turned flange, the respective ends of said inner section being slidably overlapped; and means for preventing relative rotary movement of said sections, substantially as described.

55

5. A packing ring comprising two annular split sections fitting one within the other; an annular inwardly turned radial flange at one edge of said outer section; an annular outwardly turned radial flange at one edge 60 of said inner section, said outwardly turned flange registering with the unflanged edge of said outer section; a longitudinally extending flange at the outer edge of said inner section registering with the inner edge of said outwardly turned flange, the respective ends of said inner section being slidably overlapped; and an outwardly projecting pin secured in said inner section engaging between the ends of said outer section for 65 preventing relative rotary movement of said section, substantially as described.

70

In testimony whereof I have signed my name to this specification in the presence of two subscribing witnesses.

JOHN F. KYTLICA.
